CLAIM

The ornamental design for an atomizer, as shown and
described.

DESCRIPTION

FIG. 1 is an exploded, perspective view of an atomizer
showing my new design;

FIG. 2 is a perspective view thereof;

FIG. 3 is an elevation view thereof;

FIG. 4 is a top plan view, the bottom view being the
same in appearance; and,

FIG. 5 is a perspective view, from the rear with respect
to FIG. 1.
